PORTABLE ELECTRIC POWER DRILL

William A. Douglas, South Pasadena, Calif., assignor to
The Mira Corporation, Los Angeles, Calif., a corpora-
tion of California

Filed Aug. 17, 1964, Ser. No. 81,327

Term of patent 14 years

(Cl. D54—14)

FIG. 1 is a side elevational view of a portable electric power drill, showing my new design;

FIG. 2 is a bottom view of the portable electric power drill of FIG. 1.

The side of the portable electric power drill opposite to that shown in FIG. 1 is similar to that shown in FIG. 1.

The dominant features of the design reside in the portion shown in full lines.

I claim:

The ornamental design for a portable electric power drill, as shown and described.
